ABSTRACT

A smoking pipe in a preferred embodiment having a substantially straight and unobstructed shank passage from the stem end thereof to the pipe bowl interior, with an intermittent cylindrically shaped unobstructed chamber with the stem mouth-piece angled downwardly such as to bring about a drainage of liquids within the stem and shank passage toward the bowl of the passage such that the liquids become trapped in the chamber, the reservoir including along its base section a liquid-drainage outlet reservoir port to a linear drainage unobstructed passage angling downwardly from the stem-bowl passage at an angle ranging from ten to eighty degrees and having snugly mounted therein an absorbent plug such as rolled paper or card-board of a firmness and length such that it is insertable through the passage to or into the chamber and extends out of the pipe base at the drainage outlet port, the port end of the plug around the annular sides thereof having an annular or tubular rubberized casing defining openings at opposite ends of the casing in which the end of the plug is mounted.

FIG. 8

DRY SMOKING PIPE

This invention relates to an improved reservoir pipe having a drainage outlet absorbent plug, and this application is a continuation-in-part of application Ser. No. 130,976 filed Apr. 5, 1971, now abandoned and the later application Ser. No. 215,796, entitled IMPROVED DRY SMOKING PIPE filed on Jan. 6, 1972, now abandoned.

BACKGROUND OF THE INVENTION

Prior to the present invention, the preceding parent applications of the present invention have discussed matters such as obstructions, stagnant materials collected within the pipe, the shape of the pipe bowl and the importance of the position of the outlet of the passage of the shank relative to the bowl, and the like.

SUMMARY OF THE INVENTION

An object of the present invention is to obtain a pipe having further improved structure decreasing the possibility of having stagnant drainage liquid collecting within the pipe normally impairing enjoyable taste to the smoker of the pipe.

Another object is to obtain a pipe structure and plug in combination facilitating removal of the plug and absorbed ingredients therein.

Another object is, as a combination with an improved pipe, an improved disposable plug for a reservoir.

Another object is to obtain an improved plug means facilitating the removal of moisture from the pipe without soiling or dripping on surrounding areas.

Another object is to obtain a plug of improved total absorbency.

Another object is to obtain a plug and pipe combination of improved sanitation.

Another object is to obtain an improved plug of prolonged life collectable of greater quantities of liquid.

Other objects become apparent from the preceding and following disclosure.

One or more of the preceding objects are obtained by the invention as described hereafter.

Broadly the improved structure of the present sanitary and dry smoking pipe lies in a substantially linear smoke passage extending from the stem outlet inserted within the shank jack, extending to the pipe bowl, with the smoke passage being devoid of any obstructing structure of the pipe itself, and having adjacent the stem outlet of the stem-mouth piece a chamber within the shank of the pipe, the chamber preferably being of cylindrical shape with the longitudinal axis of the cylinder preferably being colinear with the longitudinal axis of the passage extending to the pipe bowl, and with a drainage reservoir passage extending at an angle to the shank passage and chamber with the angle ranging from about 10° to about 80° and the reservoir passage being substantially linear having within the reservoir passage a removably inserted absorbent plug with a graspable end extending out of the reservoir drainage exterior outlet port. The plug graspable end extends out a predetermined distance sufficient for gripping of the plug with the fingers for removal thereof from its inserted position. Although the jack end of the shank may define a receptacle open end to the linear passage running to the pipe bowl with the receptacle being of any desired or predetermined diameter, preferably the chamber is of a diameter the same as the male insert portion of the mouth piece-stem thereby facilitating the

cleaning of the entire smoke passage with an appropriate pipe cleaner. Also as a broad part of the improved invention, the shank of the stem and the smoke passage running to the bowl interior extend at a downwardly inclined angle relative to the mouth piece-end of the stem such that the moisture passing from the smoker's mouth into the stem readily moves downwardly by the action of gravity into the smoke-passage chamber and into the reservoir passage, to thereby come in contact with the absorbent plug.

The invention also includes as a part thereof a plug which is of an absorbent composition tapered or angled at either end or at both ends — such as a rhomboid length-wise cross-section, and in an alternative embodiment tapered at neither end. In the combination of this pipe, the plug is of a sponge and/or absorbent nature whereby it withdraws the moisture from the reservoir chamber into the plug itself providing improved dry smoking devoid of the tobacco juices and saliva which would adversely affect the taste of the smoke. Typically the plug combination is cardboard, compressed paper, rolled cardboard or paper, or the like, but may be cloth or other absorbent composition. Although the plug is elongated and may be of any desired design or shape, it preferably is of a cylindrical shape, but for example may be in one embodiment of substantially squared cross-section, with the perimeter along the cross-section thereof having somewhat rounded walls. Also in one embodiment, the plug includes the above-noted preferably-annular rubberized coating near the finger-gripping end of the plug with the coating such that it facilitates the gripping as well as the sealing around the edges of the plug such that moisture does not escape from the pipe except through the breathing through-passage of the rubberized coating having the end of the absorbent composition mounted in and extending through the breathing passage of the annular rubberized coating. The plug composition includes a component and/or a coating and/or is inherently of a nature imparting a reasonable firmness or rigidity thereto, facilitatable of insertion and removal thereof from the reservoir passage. The plug may in an alternative embodiment be a tapered tube open at its tapered insertable end.

THE FIGURES

FIG. 1 illustrates an end view of a typical pipe of this invention as viewed from the bowl end of the pipe.

FIG. 2 illustrates a side cross-sectional view as taken along 2—2 of FIG. 1.

FIG. 3 illustrates an end view of a second typical pipe of this invention.

FIG. 4 illustrates a cross sectional view of the pipe illustrated in FIG. 3 as taken along lines 4—4 of FIG. 3.

FIG. 5 is a longitudinal sectional view of a straight rolled or twisted firm paper moisture absorbent plug that may be used in lieu of the sponge plug 14 of FIGS. 1 to 4.

FIG. 6 is a side elevational view of a cardboard sponge plug tapered at its opposite ends to follow the bowl contour as illustrated in FIG. 2.

FIG. 7 is a side elevational view of a paper cartridge plug similar to the plug of FIG. 5 but having a resilient annulus handle tip binder 18.

FIG. 8 is a longitudinal sectional view of a resilient rubber-like hollow liquid collection vessel plug having

a tapered open end adapted to tightly fit the lower end of the drainage opening.

DETAILED DESCRIPTION OF THE INVENTION

FIG. 1 illustrates an end view of a typical pipe 8 of the present invention, having pipe bowl 9, reservoir passage outer-port 13, and cylindrical plug 14.

FIG. 2 as taken along lines 2-2 of FIG. 1, illustrates the pipe bowl interior 10, shank 11, and stem 12 as well as the mouthpiece end 12a (FIG. 4) of the stem 12. The reservoir has a drainage outlet exterior port 13, the port can be seen in a cross-section view of the pipe bowl 9 having a shoulder 10a.

In the FIG. 4 embodiment, the port 13' extends from an underside 11a of the shank 11'. Mountably inserted within the drainage reservoir passage 11b through the port 13' is a plug 14'. FIG. 3 illustrates the end-view appearance of the FIG. 4 embodiment, such as bowl 9' and plug 14'.

As typically illustrated in FIG. 4, the length of the shank 11' is represented as 11j, one half the distance from the shank end adjacent the stem is represented as 11m, and is measured from the half-way point 11n to seven-eighths the length of the shank as indicated as 11k, the line representing 11k mark being represented by 11k'. The line representing the end of the 11j line is represented as 11j'.

The distance 11h' of the stem male insert 11h into the shank jack receptacle smoke passage 11f is measured from line 11hh to line 11g'. The remaining chamber 11e is represented by distance 11p, as measured between lines 11g' and 11k'. The end of the pipe shank 11 is located at 11b'. The narrow smoke passage 11d extends from the bowl interior 9', continues as the chamber 11e, upon extending through the chamber end wall 11c. In the chamber lower wall or floor is the reservoir passage outlet 11r communicating with the drainage reservoir passage 11b and the passage 11b exiting through reservoir exterior outlet port 13'. The exterior port 13' may be located at any point from line 11n to 11t, as represented by the measuring line 11u. The line 11t represents the extent of the measurement 11d as the measurement of one-fourth the outer width of the bowl at 11w, as measured from the shank end at line 11j'. Line 12b defines the angle 12c which normally ranges from about 2 to 6° in the downward curvature of the shank-end of the stem 12' as compared to the mouthpiece end 12a of the stem 12'.

The chamber (i.e., the remaining length) length normally varies from a beginning point at possibly as close as about three-eighths inch from the shank end to a beginning point at about seven-eighths of the shank length, for a length ending at a point at about one-half to seven-eighths of the shank length to line 11k' preferably from a point at about one-half the shank length (at line 11n) to about seven-eighths the shank length (at wall 11c). The reservoir outlet exterior port 13' is located at any point from about beneath the chamber to about seven-eighths the length of the shank (at line 11k'), in a bottom side or face of an exterior shank wall. The area in which the reservoir drainage exterior port 13' may be located is defined by line 11u. The forward edge of the exterior port may range toward the end of the bowl to about one-fourth the distance of under the bowl, as represented by the line 11t. The outside diameter of the bowl 9 is indicated by the line 11w.

It should be noted that the rubberized composition of the annulus form 15 of (FIG. 7) preferably presses against the wall of the reservoir passage 11b (when in the inserted position) pressing at a forward point of the upper portion of the port, thereby facilitating the sealing function of the plug composition. Although the plug of the invention may be compressed matter or a solid structure, or of a sponge or rubber or foam material, typically twisted firm paper is advantageous, preferably tapered to a smaller diameter length at its insertable end. A plug typically varies from about three-eighths inch to about 1½ inch in length. Additionally however the rubberized annular coating 15 facilitates in the gripping of the plug for removal thereof from the exterior port.

The angle 16 represents the angle of the longitudinal axis of the plug relative to the base 11a of the shank, this being the angle which may vary from about 10° to about 80°.

FIG. 5 absorbent plug corresponds to the FIG. 4 plug, and is a straight paper cartridge of about three-eighths to 1.5 inch.

FIG. 6 illustrates typically a cardboard tapered sponge plug, tapered at ends 17 and 17' to follow bowl contour.

FIG. 7 corresponds to the FIG. 5 embodiment except additionally including the resilient annulus tip 18.

FIG. 8 illustrates a resilient hollowed collection-vessel plug 19 having tapered open end 20.

Typically, in embodiments having a shoulder, the shoulder height varies from about one sixty-fourth up to about one-fourth the reservoir passage diameter.

Although the reservoir passage preferably is tubular with parallel opposite walls, the passage may taper inwardly.

It should be noted that any suitable or conventional absorbent composition may be employed for the absorbent plug, including non-absorbent materials which because of elasticity, and/or hydroscopic properties, and/or perforations which serve to draw into the body pipe moisture, and that any suitable or conventional plastic or rubber having necessary heat stability may be utilized as the annulus, as within the spirit and scope of the present invention. Similarly other obvious variations and/or modifications are within the scope of the invention.

I claim:

1. A smoking pipe comprising in combination: a bowl structure having inner and outer side wall surfaces and a bottom surface; a shank structure extending along a first substantially linear axis from a lowest portion of said outer bottom surface and from the side wall surfaces of the bowl structure substantially laterally in a predetermined direction to an open-ended shank-opening end; and a stem having a proximal end detachably mounted to said shank-opening end and extending distally away from the proximal end in a direction about co-axially of a longitudinal axis of said shank and shank opening end and terminating as a stem distal-end mouth-piece end portion angled slightly downwardly relative to the longitudinal axis of the shank, the stem proximal end including a male plug, and the open-ended shank-opening end having a female jack matable with the male plug, the stem defining a first passage extending from and through the mouth-piece end portion axially through the stem and opening, through the male plug; the shank defining a second passage extending

through and from the female jack end of the shank axially through the shank to and through an interior wall of said pipe bowl structure, the shank-passage defining as a part of the second passage a chamber thereof of enlarged constant diameter relative to a bowl-end of the shank-passage, and the chamber constant diameter continuing through said female jack; said shank structure further defining a reservoir-drain outlet linear passage along a second substantially linear axis at an angle ranging from about 10° to about 80° extending from an inner reservoir port forwardly toward the bowl and exiting as an exterior reservoir port on an underside of said pipe with a forward edge of the exterior reservoir port ranging forwardly up to about one-fourth the distance of under the bowl structure and rearwardly from the bowl structure to under said chamber; said chamber extending along said first linear axis as measured from said shank's jack toward the pipe bowl beginning at a point ranging from about three-eighths to about seven-eighths of said shank's length as measured from the jack end of the shank and extending toward the pipe bowl interior to a point ranging from about one-half to about seven-eighths of the shank's length as measured from the shank's jack end; said shank structure defining said chamber devoid of obstructions along said first axis; a liquid-collecting plug means of a predetermined length sufficiently long to project through said passage toward said chamber while extending forwardly generally in a pipe-bowl direction to a point outside of the exterior port when said plug means is removably insertably mounted within said reservoir-drain outlet passage, and said plug means being of sufficient predetermined cross-sectional area to plug the reservoir-drain passage, and said pipe including a stepped underside defining a shoulder through which the reservoir outer port opens, said shoulder having a height of between about one sixty-fourth inch to about one-fourth inch.

2. A smoking pipe comprising in combination: a bowl structure having inner and outer side wall surfaces and a bottom surface; a shank structure extending along a first substantially linear axis from a lowest portion of said outer bottom surface and from the side wall surfaces of the bowl structure substantially laterally in a predetermined direction to an open-ended shank-opening end; and a stem having a proximal end detachably mounted to said shank-opening end and extending distally away from the proximal end in a direction about co-axially of a longitudinal axis of said shank and shank-opening end and terminating as a stem distal-end mouth-piece end portion angled slightly downwardly

relative to the longitudinal axis of the shank, the stem proximal end including a male plug, and the open-ended shank-opening end having a female jack matable with the male plug, the stem defining a first passage extending from and through the mouth-piece end portion axially through the stem and opening, through the male plug; the shank defining a second passage extending through and from the female jack end of the shank axially through the shank to and through an interior wall of said pipe bowl structure, the shank-passage defining as a part of the second passage a chamber thereof of enlarged constant diameter relative to a bowl-end of the shank-passage, and the chamber constant diameter continuing through said female jack; said shank structure further defining a reservoir-drain outlet linear passage along a second substantially linear axis at an angle ranging from about 10° to about 80° extending from an inner reservoir port forwardly toward the bowl and exiting as an exterior reservoir port on an under side of said pipe with a forward edge of the exterior reservoir port ranging forwardly up to about one-fourth the distance of under the bowl structure and rearwardly from the bowl structure to under said chamber; said chamber extending along said first linear axis as measured from said shank's jack toward the pipe bowl beginning at a point ranging from about three-eighths to about seven-eighths of said shank's length as measured from the jack end of the shank and extending toward the pipe bowl interior to a point ranging from about one-half to about seven-eighths of the shank's length as measured from the shank's jack end; said shank structure defining said chamber devoid of obstructions along said first axis; a liquid-collecting plug means of a predetermined length sufficiently long to project through said passage toward said chamber while extending forwardly generally in a pipe-bowl direction to a point outside of the exterior port when said plug means is removably insertably mounted within said reservoir-drain outlet passage, and said plug means being of sufficient predetermined cross-sectional area to plug the reservoir-drain passage, and said plug means comprising a water absorbent composition linearly elongated in shape and having opposite terminal ends thereof, and one of said terminal ends including a binding of a resilient composition defining an annular shape.

3. The smoking pipe of claim 2 in which said resilient composition is rubberized coating shaped for facilitating the plugging of said exterior port and for providing a gripping surface.
